US00D795895S

(12) **United States Design Patent** (10) **Patent No.:** **US D795,895 S**
Brotman et al. (45) **Date of Patent:** **** Aug. 29, 2017**

(54) **DISPLAY SCREEN OR PORTION THEREOF
WITH GRAPHICAL USER INTERFACE**

(71) Applicant: **iJET INTERNATIONAL, INC.**,
Annapolis, MD (US)

(72) Inventors: **Lynne S. Brotman**, Westfield, NJ (US);
Nitzan Avitouv, Petah Tiqwa (IL)

(73) Assignee: **iJET International, Inc.**, Annapolis,
MD (US)

(**) Term: **14 Years**

(21) Appl. No.: **29/517,705**

(22) Filed: **Feb. 16, 2015**

Related U.S. Application Data

(63) Continuation of application No. 29/449,286, filed on
Mar. 14, 2013, now Pat. No. Des. 725,138.

(57) **CLAIM**

The ornamental design for a display screen or portion thereof with graphical user interface, as shown and described.

DESCRIPTION

The FIGURE is a front view of a display screen or portion thereof with graphical user interface showing our new design.

The circular dot-dash broken lines shown in the drawing represents boundaries of the claimed design. The dash-dash lines shown in the drawings represent a display screen or portion thereof with graphical user interface that form no part of the claimed design. The portions of the graphical user interface that are shown as ghosted with lower opacity represent portions of the display screen or portion thereof with graphical user interface that form no part of the claimed design.
